DESIGN FOR A PORTABLE BURNER UNIT

Styles T. Howard, Jeffersonville, Ind.

Application April 24, 1941, Serial No. 100,606

Term of patent 3½ years

To all whom it may concern:

Be it known that I, Styles T. Howard, a citizen of the United States, stationed at Jeffersonville Quartermaster Depot, Jeffersonville, Indiana, residing at 710 East 9th Street, Jeffersonville, in the county of Clark and State of Indiana, have invented a new, original, and ornamental Design for a Portable Burner Unit, of which the following is a specification, reference being had to the

accompanying drawings forming a part thereof:

Fig. 1 is a front perspective view of a portable burner unit showing my new design.

Fig. 2 is a top plan view.

Fig. 3 is a rear perspective view thereof.

I claim:

The ornamental design for a portable burner unit, substantially as shown.

STYLES T. HOWARD.
